Julian A. Bried.
INVENTOR.

UNITED STATES PATENT OFFICE.

JULIEN A. BRIED, OF OAKLAND, CALIFORNIA.

SHOE-POSITIONING DEVICE FOR SKATES.

Application filed October 27, 1921. Serial No. 510,773.

To all whom it may concern:

Be it known that I, JULIEN A. BRIED, a citizen of the United States, residing at

Oakland, in the county of Alameda and

5 State of California, have invented a new and useful Improvement in a Shoe-Positioning Device for Skates, of which the following is a specification, and which is illustrated in the accompanying drawings.

10 This invention relates to skates as used by children and youths for pleasure and exercise, either ice skates or roller skates, but particularly roller skates with handles of the improved form shown in Figures 1

15 and 2 of my former application for United States Patent filed April 13th, 1921, Serial No. 461,048.

It has for its principal object an improved shoe positioning device to take the place of

20 the toe and heel clips shown in my former application, and make it easier for a child to step on and off of such skates, particularly to step off in case of emergency even while in motion at considerable speed.

25 In the drawing accompanying this application Figure 1 is a perspective view of one of my improved roller skates, described in my former application above mentioned, and it is here shown fitted with my new

30 shoe positioning device.

Figure 2 is a plan view of a modification of the adjusting and securing means of my shoe positioning device, also showing a shoe guard for the other side of the shoe.

35 Figure 3 is an elevation of Figure 2. All parts in the several views having similar functions are numbered similarly.

In the drawing Fig. 1, the body shell of the skate is shown at 1, and the rollers are

40 indicated at 2. At 3 is shown the lower flat portion of the skate handle which is pivoted to the body at the other end of the pivot bolt 4 and is free to oscillate between the retaining strap 13 and the outside of the

45 skate body.

On top of the body where the rider's foot is placed is shown at 5 my improved shoe positioning device adjustably secured to the body by means of the screws 6—6 which

50 pass through slots in the body dotted at 7—7 and engage the nuts 8—8 beneath.

The position of the rider's shoe when upon the skate is between the flat portion of the handle 3 and the device 5, the device being

55 curvedly formed at 9 to fit against the con-

cave side of the arch of the shoe (the skate pictured in this drawing being for the right foot).

The device also has at 10 a set of points to engage the forward edge of the heel of 60 the rider's shoe, though for very young children's shoes having "spring" heels this feature may be omitted.

It will be seen that this device is much simpler than the toe and heel clips shown in 65 my former patent application mentioned and in practice is found to perform the required function much better.

In Figures 2 and 3 is shown a modification of the securing means of the adjustable 70 shoe positioning device 5 which dispenses with the screws 6 shown in Figure 1 and the necessity of using a screwdriver, and it consists in riveting the device 5 by means of shoulder rivets 6'—6' to a retaining plate 75 8' under the skate shell so that it is firm on the skate yet free to slide with the plate for adjustment in the slots 7—7 in the body.

On one edge of the retaining plate 8' are formed small teeth 12, and pivotally riveted 80 to the under side of the body at 14 is a locking plate 15 also having teeth 16 formed on it to engage the teeth of the retaining plate aforesaid and to hold it and the device 5 in adjusted position.

85 The locking plate has an end 17 extended through the shell for manipulation. The slot 19 through which this end protrudes has an offset as shown in Figure 3 so that the locking plate may be depressed at the 90 end by springing it downwards with the fingers and then moved to the right to disengage the teeth so that the positioning device 5 can be adjusted for different widths of shoes, after which the locking plate is 95 returned to the position shown in the drawing to firmly secure the device 5 in place.

At 20 in Figures 2 and 3 is shown an auxiliary plate riveted between the handle retaining and guiding strap 13 and the skate 100 body, to afford a side support for the outside of the shoe so that the handle in oscillating back and forth in riding will not rub against the shoe, thereby permitting the handle to swing freely and thus making the 105 skate easier to ride.

The shoe positioning device shown in Figures 2 and 3 is shown fitted to a skate for the left foot and should be reversed or "right handed" for the other foot.

2
I claim:

1. In a skate, a shoe receiving portion, means for positioning the outer side of a shoe thereon, a stop adjustable transversely of the skate for engaging the inner side of the shoe, and a latch co-operating with a portion of said stop for holding it in adjusted position.
2. In a skate with a handle pivoted at the side thereof, a fixed plate between said handle and the skate body to support the outer side of a rider's shoe, and a device, adjustable transversely of the skate body, formed to fit against the side of the arch of the shoe.
3. In a skate, a foot support, an upwardly extending handle adapted to be gripped by a rider on said skate, said handle being pivoted to the skate at the outer side thereof, a plate fixed to the skate between said handle and the outer side of the rider's foot to position the outer side of the shoe, and a transversely adjustable stop for the inner side of the shoe.
4. In a skate, a foot support, an upwardly extending handle adapted to be gripped by a rider on said skate, said handle being pivoted to the skate at the outer side thereof, a side stop fixed to the skate between said handle and the outer side of the rider's foot to position the outer side of the shoe on the support, and a stop co-operating with said side stop for the inner side of the shoe.
5. In a juvenile vehicle, a foot supporting body, and a shoe positioning device there-
- on formed to lie against the inner concave side of the arch of the shoe.
6. In a skate embracing a foot supporting body, means for positioning a rider's shoe thereon embracing a device formed to lie against the concave side of the arch of the shoe, said device having an extension adapted to engage the forward edge of the heel. 40
7. In a skate embracing a foot supporting body with a handle for holding the body to the foot of a rider without being otherwise secured thereto, a stop for positioning the outer side of the rider's shoe on the body against outward displacement, and a co-operating stop adapted to lie against the inner side of the shoe having an extension adapted to engage the front edge of the heel. 45
8. In a skate embracing a foot supporting body with a handle for holding the body to the foot of a rider without being otherwise secured thereto, a stop for positioning the outer side of a rider's shoe on the body against outward displacement, and a co-operating stop adapted to lie against the inner side of the shoe having an extension with teeth formed thereon adapted to engage the front edge of the heel. 50
9. A roller skate comprising a foot receiving platform, a vertically extending handle at the outer side of the platform, and a stop at the inner side thereof formed to fit against the concave side of the arch of the shoe. 55

JULIEN A. BRIED.
